FALL ROPE CARRIER STOP BUTTON

Charles C. Sunderland, New Brunswick, N. J., assignor to John A. Roebling's Sons Company, Trenton, N. J., a corporation of New Jersey

Application June 5, 1940, Serial No. 338,924

7 Claims. (Cl. 24—114.5)

The present invention relates to fall rope carrier buttons and has for one object the provision of a fall rope carrier button capable of sustaining severe shocks in either direction without shifting in position on its button stop rope.

Another object is to provide means which prevents the button from shifting and accomplishes this result without causing damage to the button stop rope itself.

The invention comprises a novel form of clamp upon which button stops varying in external diameter may be secured in fixed relation.

Other objects and advantages of the invention will appear from the following description taken in connection with the accompanying drawing, which illustrates a preferred embodiment of the invention and in which—

Figure 1 is a side elevation showing, in a general view, the relation of the fall rope carrier button, load carriage, and fall rope carriers;

Figure 2 is a vertical longitudinal sectional view through a fall rope carrier button embodying the present invention;

Figure 3 is an enlarged transverse vertical sectional view taken on the line 3—3 of Figure 2;

Figure 4 is an interior side elevation of one of the rope clamps;

Figure 5 is a transverse vertical section showing a cooperating pair of such rope clamps before they are positioned together;

Figure 6 is a detail view showing the upper or button stop cooperating portion of one of the fall rope carriers of Figure 1.

Figures 7 and 8 are side elevations of fall rope carrier buttons on a small scale, the construction being the same as in Figure 2 but illustrating the fact that the buttons are constructed with different diameters, the practice being, as viewed in Figure 1 for example, that the stop buttons from right to left thereof would have gradually increasing diameters.

Referring in detail to the drawing, and particularly to Figure 1, the load carriage 11 is provided with the usual wheels for cooperation with the hoisting ropes 12, main cable C and button stop rope 14, the arrangement being such as to maintain the button stop rope 14 at all times equally distant from the main cable C in the vicinity of the load carriage.

The load carriage 11 is provided as usual with the horn 13 which supports a plurality of fall rope carriers 15 whose function is to be detached from the load carriage as it travels from right to left, as viewed in Figure 1, at intervals determined by the spacing of the rope carrier but-

tons 18 along the button stop rope 14 and be supported by the main cable C at 20 (Fig. 6) instead of the horn 13 at 19, thus providing spaced supports for the hoisting ropes 12 and conveying ropes 12a from the main cable and at intervals along it.

It will be understood that the fall rope carriers 15, as viewed from right to left in Figure 1, are provided with progressively larger openings 16 10 (not shown) receiving the button stop rope 14 and that spaced along the button stop rope from right to left, as viewed in Figure 1, is a series of progressively larger buttons 18 (only one being shown), the first of which functions to detach 15 the first (here the right hand) fall rope carrier; the second, or next larger button to the left, functions to detach the next outside fall rope carrier from the horn, and so on.

On return travel the horn 13 enters each fall 20 rope carrier as it reaches it, so that each fall rope carrier is picked up in turn by the horn at 19 on return travel, that is, from left to right, as viewed in Figure 1, the impact shock being taken by the usual buffer 17 on the load carriage.

25 Inasmuch as these cableways operate at speeds of twelve hundred to fifteen hundred feet per minute or more, it can be seen that the button stops are subjected to constantly repeated severe shocks and that the button stops must be so constructed as to minimize the shocks to the button stop rope or cable, prevent creeping of the button stops from right to left, even over long periods of time, and at the same time accomplish this result in such a way that the button stop rope 30 itself is not damaged. It has been the practice in the past to endeavor to prevent such creepage of the button stops by twisting the button stop rope or cable to open its strands, put in an insert and release the strands so that they close 35 over the insert, leaving an enlarged portion of the cable at that point to take up shock. It is also known to open the cable further to one side of such an insert and place therein a conical insert, thus providing a conically enlarged portion of the 40 cable to receive the shock thrusts communicated to it by the button stop.

While such devices have had the effect of preventing substantial creepage of the button stops, 45 their deformation of the cable and the repeated shocks given to the cable at its deformed parts have caused sufficient damage to the cable to shorten its life very considerably.

It is one of the objects of this invention not only to prevent creepage of the button stop but

to do so by means having no damaging effect on the button stop rope or cable itself.

Referring to Figures 2 to 5 inclusive, a pair of generally semi-cylindrical interfitting sections 21 and 22 are provided, the internal diameter of the assembled sections being such as to grip the button stop rope or cable 14 tightly. This inside diameter is preferably such as to require a compression tool for lining up the lugs 23 of each section with the recesses 24 of the other. Longitudinal aligned passages 27 are provided through the interfitting lugs of each section so that when they have been brought to properly assembled cable gripping relation by means of the tool, a pin 29 may be thrust through each series of aligned openings and thereby retain the assembled cable gripping sections in desired relation.

Each cable gripping section, forming generally half a thick walled hollow cylinder, is provided with a series of internal projections 31 conforming to the lay of the cable strands, fitting in the circumferential spaces between adjoining strands and each exerting a firm grip on the cable therebetween.

At each end of the assembled cable gripping sections shock absorbing washers are provided, such as the rubber washers 35, separated by relatively thin metallic washers 37.

As already stated, the external diameters of successive stop buttons increase with each button on the button stop rope from right to left, as viewed in Figure 1. The diameters vary for example from that indicated in Figure 7 to that indicated in Figure 8, the largest diameter portion in Figure 8 being indicated by the reference numeral 18a.

Whatever the external diameter of any particular button stop, however, it is constructed interiorly as indicated in Figure 2 for cooperation with the assembled cable gripping sections 21 and 22.

The part of portion 16a of the button stop that takes the shock of detaching a fall rope carrier is indicated at 39 in Figure 2, and this portion 16a has a cylindrical interior to receive the assembled cable gripping sections 21, 22, and one end group of shock absorbing washers. Its internal diameter is reduced beyond its washer receiving portion to receive the button stop rope 14 in slidably relation therewith.

At its open end, in Fig. 2 the left end, the shock absorbing portion 16a of the button is interiorly threaded at 38 to receive the tapered nose section 40. The parts are preferably maintained in threaded assembled relation by a screw 42 whose head enters and is countersunk with respect to the shock absorbing portion 16a and whose threaded portion engages threads in an opening provided for it in the tapered nose section 40.

The relation of these parts is such that when assembled the entire assembly is rigid, and for this purpose the two parts of the button stop are proportioned so that they must be screwed tightly together before screw 42 can be inserted. Accordingly, the tapered nose portion 40 and the shock absorbing portion 16a are provided with radial openings 47 and 48 respectively, for the reception of pin wrenches by means of which they may be given relative rotation.

It will be seen that by this construction an extremely tight grip is secured upon the button stop rope, and without deforming it radially outwardly into enlarged portions. As a result the

construction withstands severe shocks without having a tendency to destroy or damage the button stop rope.

What is claimed is:

- 5 1. A fall rope carrier button construction comprising cooperating clamping members for gripping a button stop rope, and a two part fall rope carrier stop button having interior opposed compression seats and receiving within it between said seats said cooperating clamping members.
- 10 2. A fall rope carrier button construction comprising cooperating clamping members for gripping a button stop rope, said clamping members having interfitting projections and locking means cooperating with said interfitting projections for securing said members together in rope gripping relation, and a fall rope carrier stop button receiving within it and secured to said clamping members.
- 15 3. A fall rope carrier button construction comprising cooperating clamping members for gripping a button stop rope, each member having two sets of projections interfitting with projections of the other, a pin passing through each interfitting set of projections securing said clamping members together in rope gripping relation, and a fall rope carrier stop button receiving within it and secured to said clamping members.
- 20 25 4. A fall rope carrier button construction comprising externally cylindrical cooperating clamping members for gripping a button stop rope, said members having interior rope gripping projections corresponding to the lay of the rope, means for securing said clamping members together in rope gripping relation, and a two part fall rope carrier stop button having opposed end pressure exerting seats and receiving within it between said seats said clamping members, thereby gripping said clamping members under pressure exerted axially of the button.
- 30 35 5. A fall rope carrier button construction comprising cooperating clamping members for gripping a button stop rope, said members having interior rope gripping projections corresponding to the lay of the rope, each member having two sets of projections interfitting with projections of the other, a pin passing through each interfitting set of projections securing said clamping members together in rope gripping relation, and a fall rope carrier stop button receiving within it and secured to said clamping members.
- 40 45 6. A fall rope carrier button construction comprising cooperating clamping members for gripping a button stop rope, a two part fall rope carrier stop button secured to said cooperating clamping members, each part having a fall rope receiving portion and one part having an inner portion of greater diameter for receiving said clamping members, shock absorbing washer means between one end of said clamping members and said last named stop button part and aligned with its fall rope receiving portion, and shock absorbing washer means between the other end of said clamping members and the other stop button part and aligned with its fall rope receiving portion.
- 50 55 7. A fall rope carrier button construction comprising cooperating clamping members for gripping a button stop rope, said members having interior rope gripping projections corresponding to the lay of the rope, each member having two sets of projections interfitting with projections of the other, a pin passing through each interfitting set of projections securing said clamping members together in rope gripping relation, and a fall rope carrier stop button receiving within it and secured to said clamping members.
- 60 65 8. A fall rope carrier button construction comprising cooperating clamping members for gripping a button stop rope, said members having interior rope gripping projections corresponding to the lay of the rope, each member having two sets of projections interfitting with projections of the other, a pin passing through each interfitting set of projections securing said clamping members together in rope gripping relation, and a fall rope carrier stop button receiving within it and secured to said clamping members.
- 70 75 9. A fall rope carrier button construction comprising cooperating clamping members for gripping a button stop rope, said members having interior rope gripping projections corresponding to the lay of the rope, each member having two sets of projections interfitting with projections of the other, a pin passing through each interfitting set of projections securing said clamping members together in rope gripping relation, and a fall rope carrier stop button receiving within it and secured to said clamping members.

members together in rope gripping relation, a two-part fall rope carrier stop button secured to said cooperating clamping members, each part having a fall rope receiving portion and one part having an inner portion of greater diameter for receiving said clamping members, shock absorbing washer means between one end of said clamp-

ing members and said last named stop button part and aligned with its fall rope receiving portion, and shock absorbing washer means between the other end of said clamping members and the other stop button part and aligned with its fall rope receiving portion.

CHARLES C. SUNDERLAND.
